UNITED STATES PATENT OFFICE.

LOUIS A. LIEBS, OF WOODHAVEN, NEW YORK, ASSIGNOR TO L. A. LIEBS COMPANY, INC., OF NEW YORK, N. Y.

BAND ENVELOPE.

Application filed November 17, 1927. Serial No. 233,966.

This invention relates to improvements in containers for cards suitable for Easter greetings or the like, having a band of suitable material connected thereto which will 5 function not only as a binding element for packages which may accompany the cards, but also as a distinct feature of ornamentation.

A further object of this invention is to 10 provide a band envelope which will be adapted to receive greeting cards or other similar elements, means being provided integrally with the container for securely fastening to a package or other article which 15 may be intended to accompany the cards.

Other objects of this invention will appear 20 from the following detailed description of the device and as disclosed in the single sheet of drawings, which is herewith made a part of the application.

In the drawings:

Figure 1 illustrates a perspective view of the band envelope disclosing a greeting card in operative position therein.

25 Figure 2 represents a top plan view of a portion of the band envelope including the card and disclosing the means for holding the card firmly within the container.

Figure 3 illustrates a sectional view of 30 Figure 2 taken along line 3—3.

Figure 4 illustrates a sectional view of Figure 2 taken along line 4—4.

Figure 5 represents the main body portion 35 of the band envelope in open and unfolded position disclosing the flap extensions for holding the card in interlocked relationship with the container and a portion of the band extensions.

In the band envelope, according to this invention, it is preferred that numeral 1 will 40 designate the main body portion of the device, which may be made of any suitable material, such as paper, and embellished with any desired ornamentation effect. In 45 order to provide means for holding the main body portion 1 of the container in firm relationship with a package or article which is to accompany the container and the card 2 adapted to be held in the container, band 50 extensions 3 and 4 of suitable length are provided along the opposite side edges 5 and 6 of the container. The band extensions 3 and 4 may extend at any desired angle from the side edges 5 and 6, and, furthermore, it is

preferred that the band extensions 3 and 4 55 extend integrally from the outer or upper half of the main body portion 1 of the container, as clearly disclosed in Figure 5. Tongue portions 7 and 8 extend laterally a suitable distance from the side edges 5 and 6 60 and the main body portion 1 for the purpose of providing means whereby the lower half of the container may be held in firm interlocked relationship with the upper half when folded along the line 9. The tongue 65 elements 7 and 8 may be provided with gum or otherwise for fastening to the lower half of the main body portion 1 when properly folded, thereby forming a container for the 70 reception of an Easter greeting card, or any 70 other suitable element. The free ends of band extensions 3 and 4, as at 10 and 11 may be properly gummed for securely fastening to the wrapper of a package 12, or otherwise.

In operation, this invention provides a 75 band envelope including a container for cards, samples or other suitable articles, made preferably from a single piece of material, such as paper, and having a main body portion which can be easily folded into 80 the form of an envelope or container and retained in that shape by means of tongue portions properly gummed or otherwise for holding the folded portions together. Integrally extending from the main body portion 85 of the container is a band element adapted to be of sufficient length for enclosing packages or bundles, thereby forming a unitary band envelope entirely distinct from the ordinary envelopes pasted on a 90 band or box. Obviously, any desired form of embellishment or ornamentation may be included on the cards or container portions without affecting the merits of this invention.

What I claim is:

An envelope formed from a single piece of material, comprising a main body portion having upper and lower sections adapted to be brought into folded relationship, laterally extending tongue elements from the upper 100 section for holding the lower section in interlocked relationship, and band members extending at any desired angle from the side edges of the upper section for the purpose of adjustment to an article.

105 In testimony whereof I affix my signature.

LOUIS A. LIEBS.
